CLAIM

The ornamental design for a wind and noise blocker, as shown and described.

DESCRIPTION

FIG. 1 is a perspective view of a wind and noise blocker showing our new design;

FIG. 2 is a front view of the wind and noise blocker of FIG. 1;

FIG. 3 is a back view of the wind and noise blocker of FIG. 1;

FIG. 4 is a first side view of the wind and noise blocker of FIG. 1;

FIG. 5 is a second side view of the wind and noise blocker of FIG. 1;

FIG. 6 is a third side view of the wind and noise blocker of FIG. 1; and,

FIG. 7 is a fourth side view of the wind and noise blocker of FIG. 1.

The broken lines illustrate portions of the wind and noise blocker that form no part of the claimed design.

1 Claim, 5 Drawing Sheets
